UNITED STATES PATENT OFFICE.

HENRY S. NORMAND, OF WATERBURY, CONNECTICUT, ASSIGNOR TO CONSOLIDATED AMERICAN FASTENER COMPANIES, INC., OF NEW YORK, N. Y., A CORPORATION OF NEW YORK.

MACHINE FOR MAKING SNAP FASTENERS.

Application filed December 8, 1916. Serial No. 135,744.

To all whom it may concern:

Be it known that I, HENRY S. NORMAND, a citizen of the United States, residing at Waterbury, county of New Haven and State 5 of Connecticut, have invented an Improvement in Machines for Making Snap Fasteners, of which the following description, in connection with the accompanying drawings, is a specification, like characters on the drawings representing like parts.

The invention to be hereinafter described relates to machines for making snap fasteners, and more particularly to machines for making that part of such fasteners that is to 15 contain a spring for yieldingly engaging the head or projection of the other member of the fastener.

In order that such part of the fastener may be economically produced, it is desirable that 20 the metal strip in which a series of such members are formed in succession, shall be subjected to the action of a series of dies which progressively act upon the strip to form the bulges or cups as the strip is moved 25 longitudinally. Inasmuch as the dies act in succession to form the bulge or cup, it is essential that the metal strip shall be guided and fed the proper distance on each feed movement to place the bulge or cup portion 30 in correct relation to the succeeding dies, and it is important also that when the metal strip has been given a feed movement that it shall be held or locked in position during the operation of the die.

35 An important feature of the present invention, therefore, consists of a series of dies which progressively act to form bulges, or cups, and feeding means which operates directly and positively upon the metal strip 40 to effect the correct feed movement each time and insure that the bulge or cup partially formed by a previously acting die shall be in proper position for the operation of the next die of the series.

45 Another important feature of the invention consists of a clamp which acts upon the metal strip and holds it during the action of the dies.

These features of the invention are in the 50 present instance effected by means of a pawl which directly engages the metal strip, and preferably at one side of the bulge or cup longitudinally of the strip, and then is given a movement in the direction of feed equal

to the distance between the bulges or cups. 55 A guide is preferably employed to guide the metal strip between the dies, and in order that the metal strip may not bend or yield in a direction away from the pawl as the latter starts to move the metal strip in the direction of feed, the metal strip is supported opposite the pawl. This support may be variously formed, but in the present instance it comprises an extension of the guide for directing the metal strip through the machine. 60 65

The clamp is preferably of yielding character and acts upon the metal strip to hold it while the dies act and the pawl moves on its non-feeding strokes.

70 The feeding pawl is preferably located between the series of dies and the clamp, and beyond the clamp the bulges or cups after being formed by the dies are slotted for the reception of the spring arms. Obviously, 75 the slots to be cut in the sides of the bulges or cups will differ according to the size of spring, the size of the snap fasteners, character of the spring, and other considerations. Therefore, another important feature of the 80 invention consists of saws placed beyond the dies and feeding means and relatively adjustable to vary the depth and length of cut or slot formed by them in the bulges or cups. Another important feature in connection 85 with the saws, consists in a guide at one side or face of the saws and between which and the face of the saws the flat part of the metal strip passes while the bulges or cups extend between the cutting edges of the saws. 90

95 The above and other features of the invention will be hereinafter described in connection with the accompanying drawings, which illustrate one good, practical form of the invention, and the several features of the invention will then be clearly defined by the claims.

In the drawings:

Figure 1 is a side elevation of a machine embodying the present invention;

Fig. 2 is an enlarged detail in side elevation and part section to show the series of opposed dies, the guide for the metal strip, and the pawl and holder or clamp;

Fig. 3 is an enlarged plan view of the saws 105 or cutters slotting the sides of the bulges or cups;

Fig. 4 is a section on the line 4—4, Fig. 3;

Fig. 5 is an enlarged detail in end elevation showing the clamps for holding the metal strip;

Fig. 6 is a plan view of a metal strip having the bulges or cups formed therein; and Fig. 7 is a section on the line 7—7, Fig. 6.

The machine frame may be of any appropriate character suitable for sustaining the operating parts, and as shown, comprises 10 in the present instance, the uprights or legs 1 to which is secured in any suitable manner the bed plate 2, as by the bolts 3. Rising from the bed plate 2 are the uprights or stands 4, at the upper portion of which is 15 mounted the shaft 5 in suitable bearings secured to the stands 4. The shaft 5 may be rotated by any suitable means, such, for instance, as the wheel 6 about which passes a belt 7 operated from a proper source of 20 power. The wheel 6 may either be secured to the shaft 5 or detachably clutched thereto, as usual, in this general type of machine, but since these features form no part of the 25 present invention, and are well understood by those skilled in the art, they are not illustrated and need no further elucidation.

Mounted for sliding movement in the stands 4 is the slide 8, actuated by a suitable cam or crank on the shaft 5, as usual, the 30 construction being such that as the shaft 5 is rotated, the slide 8 will be raised and lowered. The details of this feature are not illustrated, because they are well understood by those skilled in the art and form no essential part of the present invention.

The slide 8 carries a series of dies and in opposed relation thereto is another series of dies, each one of the opposed dies of the series acting progressively upon the metal 40 strip to form therein the desired character of bulge or cup, as will more fully appear. In the present instance of the invention the slide 8 has secured thereto a die carrier 9 to which the series of upper dies are secured. The upper dies, which are best 45 shown in Fig. 2, are preferably made separate and secured to the die carrier 9 by suitable means such as the screws 10. Each of the dies of the upper series comprises a 50 sleeve 11 in which is secured by suitable means such as the set screw 12, a plunger 13 having projecting below its lower end the die 14. The remaining dies of the upper series are similarly constructed, except that 55 the shape of the die itself is gradually varied from one end of the series to the other so that each of the successive dies shall act upon the metal strip to gradually shape the bulge or cup into its final form. The number 60 of dies in the series may, of course, be varied, but in the present instance, six are illustrated, and are usually sufficient to accomplish the ends in view.

Mounted upon the bed plate 2 is the die block 15 which may be secured to the bed

plate by appropriate means such as the bolts 16. Rising from the die block 15 are the lower dies which correspond in number to the upper dies, and in the present instance of the invention, are six in number. These 70 lower dies may be appropriately secured to the die block 15 by the bolts 17 and flanges 18, and held in opposed relation to the upper dies. Each of the lower dies comprises a sleeve 19 having a recess therein for a block 75 20 through which passes a small plunger 21, the lower end of the plunger being seated upon a suitable spring 22, the construction being such that when the metal strip *a* is forced downward by one of the upper dies as 80 14, Fig. 2, the metal strip will be forced downwardly and cause the plunger 21 to be lowered against the action of the spring 22, and when the upper die moves away from the lower member, the plunger 21 will force 85 the metal strip upwardly so as to disengage the bulge or cup from the recess in the block 21. This enables the metal strip *a* to be properly fed longitudinally after each action of the dies, as will more fully appear. 90

Extending between the opposed dies is a guide which as a whole, is indicated at 23. This guide consists of a metal trough-like structure secured preferably above the lower dies and of a sufficient width to provide for 95 the passage longitudinally thereof of the metal strip *a*. The upper wall of the guide 23 is provided with a series of perforations 24 through which the upper dies may pass in treating the metal strip, the construction 100 being such that while the guide 23 maintains the metal strip in its correct lateral position relative to the upper and lower die members, the metal strip may move towards and from either of the dies so that when the 105 upper dies have acted upon the metal strip and formed bulges or cups therein, which are forced downwardly into the lower dies, the metal strip may be forced upwardly to disengage the bulges or cups from the lower 110 die members by the springs 22 in the lower dies, thereby permitting longitudinal feed movement of the metal strip.

In order that the bulges or cups may be properly formed in the metal strip, and that 115 each may be successively treated by the series of dies to bring the bulge or cup to its final form, it is necessary that the metal strip *a* be properly fed after each die movement to present the cup treated by a preceding die in proper position for treatment by a succeeding die. To this end, the present invention contemplates feeding in the metal strip by means which engage the bulges or 120 cups formed therein and to move the metal strip by such means a distance equal to the distance between two of the bulges or members. A suitable means to this end is illustrated most clearly in Fig. 2, wherein the die block 15 has a guideway 25 in which is 125

longitudinally movable a pawl carrier 26 having an upturned end portion 27 to which is pivotally mounted at 28, a feed pawl 29, the end 30 of which is adapted to engage the 5 bulges or cups, as indicated in Fig. 2, and by movement of the pawl carrier and the pawl in a direction longitudinally of the metal strip *a* when thus engaged by a cup or bulge, to positively feed the metal strip 10 the required distance to bring the bulges or cups being treated by the dies in succession to their appropriate dies. The pawl 29 is normally under the influence of a spring 31, whereby it is held in contact with the metal 15 strip as the pawl carrier 26 is moved longitudinally in either direction.

In order to prevent the metal strip *a* from bending or being deflected by the pawl 29 as it presses against the face of the strip or 20 engages the bulges or cups 32 to feed the metal strip longitudinally, the latter is supported in opposition to the pressure of the pawl so that it cannot be bent or deflected. This support for the metal strip may be 25 variously formed, but in the present instance of the invention, the guide 23 is extended beyond the series of dies as at 33, Fig. 2, and at this point it is preferably not provided with perforations such as are formed in the 30 guide 23 for the passage of the dies, the construction being such that as the pawl 29 is moved back and forth in engagement with the metal strip, the latter is prevented from being deflected by the pawl, and the pawl is 35 enabled to positively engage against the side portions of the bulges or cups 32 and push thereagainst, to move such strip *a* longitudinally the required distance of one feed movement.

40 The pawl carrier and pawl may be suitably actuated in the manner described, as for instance, by means of an arm 34 pivotally mounted at 35, Fig. 1, to the stands 4 and having a pin and slot connection 36 at its 45 lower end with the pawl carrier 26. The upper end of the arm 34 carries a pin or roller 37 which travels upon the periphery of the cam 38, and a spring 39 acting upon the lower portion of the arm 34, holds the 50 pin or roller 37 normally against the cam, the construction being such that as the shaft 5 rotates and carries with it its attached cam 38, the arm 34 will be moved to reciprocate the pawl carrier and pawl the required 55 distance of a feed movement.

When the feed pawl moves on its non-feeding stroke it is desirable that the metal strip *a* be held from movement with the pawl and also permit the pawl to slip over 60 the next bulge or cup 32 to be engaged by it. The present invention, therefore, contemplates a clamp located beyond the feed pawl for clamping or holding the metal strip when the feed pawl is making its non- 65 feeding stroke.

The clamp for thus holding the metal strip may be variously formed, but in the present instance of the invention, it comprises a plate 40, Figs. 2 and 5, extending transversely of the extension 33 forming a 70 backing or support for the metal strip as hereinbefore described. Extending through the backing or support 33 are the pins 41 which, below the support 33, are secured to the plate 40 as indicated in Fig. 5, preferably by being screw-threaded thereto as at 42. The plate 40 is held yieldingly against the support 33 by means of the springs 43 interposed between the heads 44 of the pins 41 and the support 33. In order that the 75 clamp shall not interfere with the proper feed movement of the metal strip by engaging the bulges or cups as the metal strip is fed through the clamp, the plate 40 is provided with a passageway 45 of sufficient 80 dimensions to permit the passage of the bulges or cups 32 therethrough. The side portions of the metal strip *a*, however, are held between the lower surface of the support 33 and the top surface of the plate 40, 85 the construction being such that the plate 40 under the action of the springs 43, will maintain the metal strip *a* from movement as the pawl carrier and pawl move on the non-feeding stroke, and will permit the metal 90 strip to pass longitudinally in its feeding stroke under the action of the pawl. Of course, the clamp may be otherwise formed and instead of being secured to the extension or support 33 of the guide 23, it may be 95 formed or supported separately therefrom, but the construction described is a good, practical form of this feature of the invention. This clamping device serves both to prevent the retreat of the metal strip on the 100 non-feeding stroke of the pawl, and to hold the strip in proper relationship to the cutting saws 51, described below.

As the dies form the bulges or cups 32, it is desirable that the metal strip be perforated as at 46, Fig. 6, to provide means for securing the completed member of the snap fastener to the clothing. This perforating may be done at the same time that the cups 32 are formed by small punches, which form 110 no part of the present invention, of the kind shown in the Kiessling Patent No. 1,326,132.

After the bulges or cups have been formed in the metal strip, it is desirable that the side portions of the bulges or cups shall 115 be slotted for the accommodation of the usual spring held in this member of the fastener. As a means to this end, the present invention provides a pair of saws, and in order that these saws may form a cut of 120 proper dimensions or may be associated to accommodate the bulges or cups of varying sizes, the saws are adjustable towards and from each other, as will presently appear.

Secured to the base plate 2, as by means 130

of the bolt 47, Fig. 1, is a bracket 48, in which are mounted the bearings 49 for supporting the saw-operating shafts 50, to the upper end portions of which are secured the 5 saws 51. Extending transversely of the bearings 49 for the saws, are plates 52 which are secured at their ends as by screws 53 to the bracket 48. Passing loosely through each of the plates 52 is an adjusting screw 10 54 which is threaded into the bearing 49 of each of the saws. Threaded into the plates 52, each with its end bearing against the surface of the bearing 49 of each saw, are adjusting screws 55, the construction being 15 such that by loosening the screws 54 and tightening up the screws 55, the saws may be adjusted towards each other in their own plane and then by tightening the screws, may be held in adjusted position. Likewise, 20 by loosening the screws 55 and tightening up the screws 54, the saws may be adjusted from each other in their own plane in accordance with the requirements of the work. The described adjusting means for the saws 25 constitutes a good, practical form of the invention, but obviously, the invention is not circumscribed by the details.

The lower ends of the saw shafts 50 are each provided with a gear 56 whereby they 30 are rotated in unison, and one of the saw shafts 50 is provided with a belt pulley 57 which may be driven by a suitable belt 58 leading to any desired source of power. From the construction described, it will be 35 apparent that while the saws may cut the desired slots 59, Fig. 7, in the sides of the bulges or cups 32, they may be adjusted towards or from each other to vary the character of cut or to accommodate them to 40 varying sizes of bulges or cups formed in the metal strip.

In order that the bulges or cups in the metal strip may be properly presented to the action of the saws, there is provided in 45 the present instance of the invention, a guide 60 extending between the saws and overlapping the surface or faces of the saws as indicated in Fig. 4, the construction being such that the bulges or cups extending from the 50 metal strip *a* will project between the cutting edges of the saws while the flanges of the metal strip at each side of the bulges or cups will be held between the lower surface of the guide 60 and the top surface of the 55 saws.

What is claimed is:—

1. In a machine of the character described, the combination of an upper series of dies and a lower series of dies for forming bulges 60 or cups in a metal strip, a guide for the metal strip secured in fixed position between and extended beyond the series of dies, a yielding clamp secured to the guide beyond the series of dies, a feed pawl between the 65 series of dies and clamp for engaging the

bulges or cups formed in the metal strip by the dies, and means for reciprocating the pawl between the series of dies and clamp to feed the metal strip after the operation of the dies. 70

2. In a machine of the character described, the combination of a series of upper and lower dies, a guide for a metal strip extending between and beyond the series of dies, said guide having a perforated portion between the dies and a non-perforated portion beyond the dies, a feed pawl opposite the non-perforated portion of the guide for engaging the bulges or cups formed in the metal strip by the dies, and means for operating the pawl to cause it to feed the metal strip longitudinally. 75 80

3. In a machine of the character described, the combination of a series of upper and lower dies, a guide for a metal strip extending between and beyond the series of dies, said guide having a perforated portion between the dies and a non-perforated portion beyond the dies, a feed pawl opposite the non-perforated portion of the guide for engaging the bulges or cups formed in the metal strip by the dies, means for operating the pawl to cause it to feed the metal strip longitudinally, and a clamp for holding the metal strip after each feed movement. 85 90 95

4. In a machine of the character described, the combination of a series of opposed dies for forming bulges or cups in succession in a metal strip, a guide for the metal strip having a portion extended beyond the series of dies, a yielding device carried by the extended portion of the guide to yieldingly engage and hold the metal strip, and a feed pawl for engaging the metal strip between the series of dies and yielding device for feeding the metal strip longitudinally. 100 105

5. In a machine of the character described, a series of opposed dies for forming bulges or cups in succession longitudinally of a metal strip, a guide for the metal strip extended beyond the series of dies, a yielding plate connected to the extended portion of the guide and between which and the guide the metal strip is passed, a pawl for engaging the metal strip between the 110 115 series of dies and yielding plate, and means for causing the pawl to feed the metal strip longitudinally between the guide and metal plate.

6. In a machine of the character described, the combination of a series of opposed dies for forming bulges or cups in succession in a metal strip, a clamp for holding the metal strip beyond the dies, a feed pawl between the dies and clamp for engaging the bulges or cups formed in the metal strip, and means for operating the pawl to cause it to feed the metal strip longitudinally. 120 125

7. In a machine of the character de- 130

scribed, the combination of a series of opposed dies for forming bulges or cups in succession in a metal strip, a clamp for holding the metal strip beyond the dies, a 5 feed pawl between the dies and clamp for engaging the bulges or cups formed in the metal strip, a guide or support for the metal strip for holding it in position for engagement by the pawl between the dies and 10 clamp, and means for operating the pawl to cause it to feed the metal strip longitudinally.

8. In a machine of the character described, the combination of a series of opposed dies for forming bulges or cups in 15 succession in a metal strip, a clamp for holding the metal strip beyond the dies, a feed pawl between the dies and clamp for engaging the bulges or cups formed in the metal strip, means for operating the pawl to cause it to feed the metal strip longitudinally, and saws beyond the clamp for slotting the bulge or cup.

9. In a machine of the character described, the combination of a series of opposed dies for forming bulges or cups in a 25 metal strip, means for engaging the bulges

or cups to move the strip longitudinally, means for holding the metal strip after each feed movement, a pair of saws and a 30 guide between the saws to position the bulges or cups for the action of the saws.

10. In a machine for making parts of snap fasteners, a series of dies for forming bulges or cups in a metal strip in succession, a pair 35 of saws for slotting the bulges or cups, and a guide at one side or face of the saws between which and the face of the saws the metal strip is passed with the bulges or cups extending between the cutting edges of the 40 saws.

11. In a machine of the character described, the combination of opposed dies for forming a series of bulges or cups in a metal 45 strip, a guide for the metal strip located between the dies, and means co-operating with one of said dies tending to press the strip up against said guide and prevent hindrance from the bulges or cups to the advance of said strip during the feed stroke of the 50 reciprocating pawl.

In testimony whereof, I have signed my name to this specification.

HENRY S. NORMAND.
